UNITED STATES PATENT OFFICE.

CHARLES WHITNEY STEVENS, OF CHICAGO, ILLINOIS, ASSIGNOR TO STEVENS PARTITION AND FLOOR DEADENER CO., OF CHICAGO, ILLINOIS, A CORPORATION OF ILLINOIS.

FLOOR CONSTRUCTION.

1,418,742.

Specification of Letters Patent. Patented June 6, 1922.

Application filed March 10, 1917. Serial No. 153,968.

To all whom it may concern:

Be it known that I, CHARLES WHITNEY STEVENS, a citizen of the United States, residing at Chicago, in the county of Cook and State of Illinois, have invented new and useful Improvements in Floor Constructions, of which the following is a full, clear, concise, and exact description, reference being had to the accompanying drawing, forming a part of this specification.

My invention relates to floor construction, and, more specifically, to a fireproof floor construction provided with means for preventing transmission of sound and vibrations.

One of the objects of my invention is to provide such a construction which will be efficient, durable, light and cheap, and which can be quickly installed. Further objects will appear from the detailed description to follow and from the appended claims.

In the drawings, in which one embodiment of my invention is shown—

Fig. 1 is a vertical section showing a fireproof floor construction embodying my invention;

Fig. 2 is a plan view of the floor construction, the upper finishing floor being removed;

Fig. 3 is a plan view showing part of the partition construction;

Fig. 4 is a vertical section on an enlarged scale showing one of the cushioning supports;

Fig. 5 is a section on the line 5—5 of Fig. 4; and

Fig. 6 is a plan view of the cushioning support.

Referring to the drawings in detail, the floor construction shown comprises a lower floor of wet-laid fireproof material, such as cement or concrete 10 laid over and between the hollow tiling 11 and supported in any suitable manner, as by steel reinforcing rods 12, a plurality of cushioning supports 13 bearing on the floor, a plurality of nailing strips 14 bearing on the supports 13, a finishing floor 15 resting on the nailing strips 14 and secured thereto, and a filling 16 of dry, cellular, fireproof aggregate, such as cinders, substantially filling the space between the floors 10 and 15. Suitable fire-stops 17 of concrete or other suitable material are provided at intervals to

prevent the spread of fire between the floors 55 10 and 15.

A fireproof partition 18 may be provided between adjacent rooms, comprising hollow tile 19 resting on cushioning supports 20 supported on the lower floor 10.

Each of the cushioning supports 13 comprises a U-shaped sheet-metal member 21, which receives the cushioning pad 22, of cattle hair or other suitable material, and a sheet-metal base 23 firmly secured to the 65 member 21 by means of rivets 24 and having foot portions 25 which are imbedded in cement mounds 26 placed on the floor 10. The foot portions 25 of the base are provided with apertures 27, through which the 70 cement in the mound 26 is forced when the base 23 is being placed in position.

The supports 13 are leveled up while the cement is still soft by means of a straight-edge, the foot portions 25 of each of the 75 supports 13 being pushed down into the cement mounds 26 to bring all of the supports to the same level. The supports are placed at such a height that ample clearance is provided between the nailing strips 80 14 and the floor 10 for the gas, water, electric and other conduits laid on the lower floor 10, as indicated in Fig. 4, one of such conduits 28 being shown extending under the nailing strips 14. The distance between 85 the supports 13 is such that the nailing strips are supported without appreciable sagging between the supports, the supports for each nailing strip being set about eighteen inches apart and the nailing strips themselves having about sixteen inches between centers.

After the nailing strips are in position, the filling of dry cinders is spread on the floor 10 up to about the level of the tops of the nailing strips 14, care being taken to fill the spaces under the nailing strips and under the supports 13. The cinder fill for this purpose may be obtained by screening, using a one-half inch mesh screen. This 100 cinder filling also assists in deadening the sound, in that it prevents what is known as a "drum" effect (which occurs when the space between the two floors is simply an air space) by preventing the vibrations of one 105 floor from being transmitted to the other through the medium of the confined air. It also tends to localize a fire by preventing

the flames from sweeping along between the floors 10 and 15, and it protects the arch or floor beneath from the heat, which tends to crack it, in case of a fire.

- 5 The cellular structure of the cinders makes them very effective as sound deadeners. Their lightness permits the use of lighter steel sections in the building construction than can be used with other heavier fireproof 10 constructions. The fireproof floor can be quickly constructed, as the finishing floor can be laid as soon as the dry cinder fill has been put in place, which would not be the case in a construction in which a concrete 15 filling is placed between the lower and upper floors and around the pipes, as this concrete filling has to dry before the finishing floor can be laid; otherwise the finishing floor would warp. With the concrete filling 20 it may be necessary to wait for weeks before the finishing floor can be laid. Also, with a fireproof floor constructed according to my invention, the finishing floor may be made level, which is impossible with a construction 25 in which cinder concrete is placed between the upper and the lower floors and around the pipes and the nailing strips imbedded in this cinder concrete, as the cinder concrete causes the nailing strips to warp 30 and also crushes down in spots, resulting in an uneven finishing floor.

I claim as new and desire to secure by Letters Patent:

1. In a building floor construction, the 35 combination with a level lower floor, of a plurality of cushioning supports on said

lower floor having their supporting surfaces elevated well above the lower floor, nailing strips carried by said supports with their lower edges well above the lower floor, an 40 upper floor laid on and secured to said nailing strips, and a filling of dry cinders substantially filling the space between said floors.

2. In a building floor construction, the 45 combination with a level lower floor of wet-laid fire-proof material, of cushioning supports arranged in rows on said lower floor having their supporting surfaces elevated well above the lower floor line, said supports 50 being suitably spaced apart, nailing strips carried by said supports with their lower edges well above the lower floor and without appreciable sagging between the supports, an upper floor laid on and secured to said 55 nailing strips, and a filling of dry cinders substantially filling the space between the said floors and beneath the nailing strips.

3. In a building construction, the combination with a lower floor of fire-proof material, 60 of a partition of fire-proof material, a plurality of cushioning supports for said partition, said supports resting on the lower floor and elevating the partition above same, upper flooring also supported by and elevated above the lower floor, and a dry cinder 65 filling between the floors and beneath the partition.

In witness whereof, I have hereunto subscribed my name.

CHARLES WHITNEY STEVENS.
